UNITED STATES PATENT OFFICE.

HERBERT H. FREY, OF CHICAGO, ILLINOIS.

APPARATUS FOR COMPRESSING AIR.

1,108,984.

Specification of Letters Patent.

Patented Sept. 1, 19

Application filed December 23, 1912. Serial No. 738,168.

To all whom it may concern:

Be it known that I, HERBERT H. FREY, a citizen of the United States, residing at Chicago, in the county of Cook and State of Illinois, have invented a certain new and useful Improvement in Apparatus for Compressing Air, of which the following is a full, clear, concise, and exact description, reference being had to the accompanying drawing, forming a part of this specification.

My invention relates to apparatus for compressing air and the object of my invention is to provide a device for that purpose which itself is operated by air compression so that it may be applied to an otherwise idle cylinder of an internal combustion engine and be operated by the air compressed by the piston in said cylinder.

The device of my invention is particularly adapted for use in the automobile industry, since it may be employed for pumping up tires and may be operated automatically by merely substituting it for one of the spark plugs of the engine of an automobile.

My present invention is particularly concerned with the provision of certain improvements over the form of apparatus for compressing air shown and described in my Patent No. 1,001,132 granted August 22d, 1911. My aforesaid patent discloses apparatus for compressing air comprising a so-called "breather valve." In my present application I describe and claim an improved "breather valve," which is illustrated in combination with compounding mechanism whereby extremely high pressures may be obtained in comparatively short periods of time.

Structurally my invention comprises a compression cylinder and a power cylinder, the former being of smaller diameter than the latter; each of said cylinders having a piston member reciprocating therein. These piston members are mechanically connected and the piston in the power cylinder is subject to the compression formed in the engine cylinder with which it is associated. Under the influence of the compression formed in the engine cylinder, the piston in the power cylinder, which I shall call the power piston, is moved intermittently in one direction while the return movement is secured by the suction produced by the piston in the engine cylinder, the air cushion which is

formed in the top of the power cylinder and whatever effect gravity may have.

The power piston and the piston which operates in the compression cylinder, which I shall call the compression piston, may, if desired, be cast to form one integral unit. Leading from below the power piston to a point above the compression piston, is a valved passage. This valved passage has communication with a stem carried by the lower end of the casing of the power cylinder, through which stem the power cylinder has communication with the engine cylinder. Due to the presence of the valved passage just mentioned, previously compressed air at a pressure higher than atmospheric pressure, is passed from the engine cylinder into the compression cylinder before the upward movement of the connected pistons is commenced.

Located in the stem which connects the power cylinder with the engine cylinder, is a valve which I call the "breather valve." My present invention is particularly concerned with certain improvements in this so-called "breather valve". This "breather valve" comprises a valve seat located in the side of the stem, a valve member for said seat, and a spring for normally retaining said valve member in position upon its seat, said spring extending across the opening in said stem and bearing against the wall of said stem at a point diametrically opposite said valve member.

My invention also has to do with certain valved passages whereby air at atmospheric pressure is admitted to the compression cylinder and whereby compressed air is passed from the compression cylinder into a hose and thence to a tire which is to be inflated, or other container for compressed air. Certain cushioning devices are provided to prevent pounding of the pistons within their respective cylinders.

These and other features of the device of my invention are disclosed in detail in the following description and are illustrated in the accompanying drawing in which the device of my invention and the engine cylinder associated therewith are shown in longitudinal section.

The power cylinder is illustrated at 1, and it will be seen that this power cylinder has a central boss 2, extending downwardly therefrom, said boss being provided with a

reduced portion 3, externally threaded in order that said reduced portion may be screw threaded into the spark plug opening of a gas engine cylinder illustrated at 4. 5 The piston for the cylinder 4, is illustrated at 5. Cast integrally with the power cylinder 1, is the compression cylinder 6, which is of smaller diameter than the power cylinder and is disposed concentric therewith. 10 The compression cylinder is provided with suitable cooling flanges 7, as shown. Located a short distance below the annular shoulder 8, are a plurality of apertures 9, the purpose of which will be hereinafter described. Located in the top of the compression cylinder 6, is a ball check valve 10, seating against atmospheric pressure, and a ball check valve 11, seating against pressure within the compression cylinder 6. The air 15 taken off through the check valve 11, passes through a suitable nipple 12, to which is secured a hose 13, as shown.

Disposed within the power and compression cylinders are the power and compression pistons, illustrated at 14 and 15, respectively. These pistons constitute an integral unit, as shown. Each of the pistons is provided with suitable packing rings 16, as illustrated. Extending from a point below 20 the power piston to a point above the compression piston, is a central passageway 17, which is enlarged at 18, and 19, as shown. Located in the enlarged portion 18, of the passageway 17, is a ball check valve 20, seating against pressure coming from the power cylinder. This check valve comprises a ball normally held upon its seat by a spring, bearing against and disposed around a reduced portion of a plug 21, threaded into 25 the passage 17, as shown. This plug is provided with a plurality of apertures indicated at 22.

Threaded into the central bore of the boss 2, is a projection 23, which, when the 45 pistons are in the position shown in the drawing, is located within the enlarged portion 19, of the passageway 17, as shown. This projection 23, is provided for the purpose of cushioning the power piston on its 50 down stroke. In practice there is necessarily a slight clearance between this projection 23 and the piston 14, in order that air may leak around the projection and get under the power piston 14.

55 The central boss 2, is provided with a transverse bore intersecting the central passage therethrough. Located in this transverse bore is a tapered stop cock 24, provided with a handle 25, as shown. This stop cock 60 is provided with a transverse passageway 26, which when the stop cock is in the position shown in the drawings is in effect a part of the central bore through the boss 2, which boss constitutes the stem for the device in question. The central bore through

the boss is illustrated at 27. Threaded into the stop cock 24, as shown, is a valve seat 28, provided with a flange 29, adapted to engage the boss 2. Bearing against the seat is a ball 30, which is normally held in position by means of a spring 30^a, extending directly across the central bore through the stem and bearing in a suitable socket 31, as illustrated.

70 The operation of the device of my invention is as follows: On the up stroke of the piston 5 within the engine cylinder 4, air is compressed above the piston 5, and is forced through the stem, projection 23, and valved passage 17, into the compression cylinder. When the pressure within the compression cylinder is equal to or substantially equal to the pressure within the cylinder 4, the valve 20, is seated. The pistons are then moved upward due to the increasing pressure within the cylinder 4, air leaking around the projection 23 to a point below the piston 14. Due to the difference in the diameter of the power and compression pistons, the air within the compression cylinder is raised to a high pressure, and is taken off through check valve 11 and hose 13. When the power piston 14 has passed the holes 9 in the wall of the power cylinder, air is trapped in the annular space above these holes, this air serving as a cushion to prevent the power cylinder pounding against the annular shoulder 8. Upon the down stroke of the piston 5, the pistons 14 and 15, are drawn downwardly, due to the partial vacuum produced by the piston 5. At the same time air at atmospheric pressure is supplied to the engine cylinder through the breather valve. Upon the down stroke of the pistons, air passing in through the intake valve 10, prevents the production of a vacuum in the compression cylinder. When, upon the down stroke, the projection 23 enters the enlarged portion 19, of the passageway 17, a quantity of air is trapped below the power piston and serves as a cushion to prevent the power piston pounding against the bottom of the power cylinder. The next upward stroke of the piston, within the engine cylinder again raises the power and compression pistons within their respective cylinders. Due to inertia and friction, the pistons 14 and 15 do not start upon their upward travel until a certain pressure is developed within the compression cylinder. The operation above-described may be continued as long as the operation of the piston 5 within the engine cylinder 4, is continued.

105 What I claim and desire to secure by Letters Patent of the United States is:

110 1. In a device of the class described, a pair of differential cylinders, connected pistons in said cylinders, the lower end of the larger cylinder being provided with a stem 115

having a passage therethrough, and a breather valve controlling communication between said passage and the atmosphere, said breather valve comprising a seat located 5 at one side of said passage, a valve member, and a compression spring normally holding said valve member against said seat, said spring bearing against said valve member and extending across said passage to the 10 opposite side thereof.

2. In a device of the class described, a pair of differential cylinders, connected pistons in said cylinders, the larger cylinder being provided with a stem, a passage 15 through said stem, and a breather valve controlling communication between said passage and the atmosphere, said breather valve comprising a seat located at one side of said passage, a valve member and a spring nor-

mally holding said valve member against 20 said seat, said spring being located within said passage.

3. In a device of the class described, a power cylinder, a piston in said cylinder, a stem carried by the lower end of said cylinder, a passage through said stem, and a breather valve, said breather valve comprising a valve member and a spring normally holding said valve member against its seat, 25 said valve member and spring being located in the passage through said stem.

In witness whereof, I hereunto subscribe my name this 20th day of December, A. D. 1912.

HERBERT H. FREY.
